UNITED STATES PATENT OFFICE

JOSEPH A. COY, OF NORWOOD, OHIO, ASSIGNOR TO THE WADSWORTH ELECTRIC MANUFACTURING COMPANY, OF COVINGTON, KENTUCKY, A CORPORATION OF KENTUCKY

LIGHTING STRUCTURE

Application filed September 18, 1930. Serial No. 482,763.

This invention relates to means for illuminating a defined area.

An object of the invention is to provide such means which effect a uniform distribution of light.

Another object is to provide means by which the illuminated area may be restricted or enlarged by simple adjustments.

Another object is to provide means for readily changing the intensity of illumination without affecting the even diffusion of light.

Another object is the provision of ventilating means for carrying off the heat developed by the lighting elements.

Another object is to provide means of the class described which comprise a minimum of parts and which are inexpensively manufactured and easily assembled by persons unskilled in such work.

These and other objects are attained by the means described herein and set forth in the accompanying drawings, in which:

Fig. 1 is a fragmental perspective view of assembled lighting means of the present invention, with parts broken away.

Figs. 2 and 3 are fragmental perspective views of means used for modifying the area of illumination.

Fig. 4 is an end elevational view of means of this invention as applied to a built-in form of lighting trough.

Fig. 5 is a transverse cross-sectional view through one of the receptacles and support means of the present invention.

Fig. 6 is an edge view of one of the louvers provided herein.

Figs. 7 and 8 are fragmental perspective views of modified louver means of this invention.

Fig. 9 is a detail view of an end plate.

Heretofore the installation of window-lighting fixtures has been a problem to be worked out by the individual skilled workman or electrician. The means and methods have been various and consequently involved and expensive. The chief expedient heretofore has been to provide a channel opening in the ceiling of show windows along the front and having pre-arranged louver units

secured in the bottom of the channel after positioning of the lamp sockets, reflectors and lamps. The adjacent louver units were provided with end abutment frames which cast a shadow at various places in the lighted area. A still more uneven lighting effect resulted from the use of the simple reflector and lamp.

This invention overcomes these difficulties by providing an inverted trough having a narrow ledge at each lower edge for receiving a series of self-spacing louvers above which the lighting and reflector means are situated. Interchangeable reflectors are provided for one side whereby the angle and area of illumination are made adjustable. Means are likewise provided for supporting the light globes at the correct level despite the use of the various sized globes in changing the intensity of illumination.

With reference to the drawings: The upper structure consists of a plate 10 having lateral, downwardly-projecting flanges 11. Side walls 12 and 13 are suitably secured to said flanges. Angle strips 14 are oppositely disposed at pre-determined levels, upon the inner faces of walls 12 and 13. A curved reflector panel 15 is secured upon the lower edge of wall 12. Panel 15 normally constitutes the front or constant reflector of the device. A reflector panel 16, of less convexity than panel 15, is removably secured upon the lower edge of wall 13. Both panels are provided at their lower edges with the inwardly and horizontally projecting flanges or ledges 17 and 18. A support plate 19 having the central longitudinal aperture 20 therein, is adapted to be supported horizontally upon one of the pairs of strips 14. A receptacle 21 is adapted to be positioned upon the upper face of plate 19, with its lower portion 22 projecting downwardly through aperture 20. Portion 22 has attached therein the lamp receiving socket 23, the inner face of which threadedly receives the stem of the light globe and the outer face of which threadedly receives the fastening member 24. Receptacle 21 is provided with a removable lid 25, for permitting access to the wiring within, and with perforations 26 for

- allowing passage of the wires from one receptacle to the next. It is obvious that receptacles 21 may be moved longitudinally of support plate 19 for suitably spacing a greater or lesser number of globes. In the event that a set of lamps of greater length than, for example, the one shown in Fig. 1, is to be used, then the support plate 19 is positioned upon the uppermost pair of strips 14, or if the lamps are shorter, then the lowermost pair of strips is utilized, so that the lamp filaments will be held in such position relative to the reflector panels that the light will be properly deflected. It should be noted that an induced current of air may be passed through the channel provided between plates 19 and 10 and walls 12 and 13 whereby the heat generated by the electric lamps may be effectively carried off.
- 20 The louvers 27 comprise each a flat strip, preferably of metal and having an inwardly offset spacing arm 28 at each end, the arms extending from opposite sides of the strip. Louvers 27 are adapted to be positioned edgewise upon the flanges 17 and 18, the end of each arm 28 contacting a face of the adjacent louver for effecting uniform spacing. Modified louver means are illustrated in Figs. 7 and 8. In the one, (Fig. 7) the spacing arms 29 are adapted to lie flat upon flanges 17 and 18 and are provided with end ears 30 for abutting the adjacent louver. The ends of the louver strip are rounded on the upper portions to preclude interference with the reflector panels when the louvers are tilted, as will be explained. In Fig. 8, the toothed, upwardly projecting flange 31 is substituted for the flanges 17 and 18. Each end of the modified louver 32 is received between a pair of the flange teeth, being provided with the end projections 33 for this purpose.
- For increasing the area of illumination as effected by the structure in Fig. 1, two panels, 34 and 35 respectively, of less width than panel 16, are provided. Their approximate relationships with constant panel 15, are shown in dotted lines, Fig. 1 and in Figs. 2 and 3. Panels 34 and 35 are attached to wall 13 in the same way as panel 16. Panel 34 effects a limited, and panel 35, a greater increase in the area illuminated. The sets of louvers used with panels 34 and 35 are preferably made with short end sections 36 extending parallel with one another but in planes spaced apart a distance corresponding to that between constant flange 17 and the flange 18 of the removable panels 34 and 35, respectively, when in position.
- 60 In Fig. 4 the last-explained type of louver is shown as used with a built-in trough 37 having the ordinary reflector 38 positioned therein. In this case the louver supporting means on one wall may consist of the ribbon strip 39 while the opposite wall may be

provided with one or with a plurality of molding strips 40 at different heights. The lighting apparatus of this invention is adapted to be manufactured in convenient lengths which may be joined to form a unit of greater length by a slight overlapping at the ends of walls 12 and 13 and reflectors 15 and 16, these being joined by means of suitable clamps or bolts passing through perforations 41. At the ends of the installed unit, end plates 42, (Fig. 9) may be positioned by utilizing the same perforations. The lightness of the material used for the device renders such adjustments easily effected.

What is claimed is:

1. Illuminating means comprising an inverted trough member having side portions forming light reflectors, means in the upper part of said member for adjustably suspending lighting elements between said reflectors, supporting means at the bottoms of said reflectors and louvers comprising strip members adapted to be mounted upon said support means transversely of the trough member.

2. Illuminating means comprising an inverted trough member comprising downwardly depending side walls with an upper cover plate attached thereto, a reflector panel secured to the lower edge of one of said walls, removable reflector panels of different widths adapted to be selectively attached to the lower edge of the other of said walls for varying the area of illumination, an apertured support plate positioned between said side walls, means for disposing said plate in adjusted positions, a receptacle supportable upon said plate and having a socket portion adapted to project downwardly through the aperture of said plate for suspending a lighting element between said reflector panels, support means on the bottoms of said reflector panels and louvers adapted to be supported by said means transversely of the trough member and comprising strips with laterally projecting arms at the ends thereof for disposing said strips in edgewise position and for abutting adjacently-positioned strips to effect uniform spacing of the louvers.

3. A lighting trough comprising a pair of spaced walls with a longitudinally-extending cover plate removably attached thereto and forming a third wall, means associated with said walls for suspending lighting elements at variable distances below said walls, a reflector panel secured to the free, longitudinal edge of one of said walls, and removable reflector panels of different widths adapted to be selectively attached to the free longitudinal edge of the other of said walls for varying the illuminated area controlled by the reflector trough.

4. A lighting trough comprising a pair of spaced walls with a longitudinally-extending cover plate removably attached thereto, a

reflector panel secured to the free longitudinal edge of one of said walls, removable reflector panels of different widths adapted to be selectively attached to the free longitudinal edge of the other of said walls for vary-

5 ing the angle of illumination controlled by the reflector panels, oppositely disposed support members secured upon the inner faces of said walls, an apertured plate member adapted to be supported upon selected pairs 10 of said support members, and receptacles supportable upon said plate member across the aperture thereof and movable longitudinally of the plate, said receptacles being adapted to suspend lighting elements between the reflector panels, the space between said support and cover plates being adapted 15 to serve as a wiring and ventilating channel.

20 5. The combination of a lighting trough having downwardly-projecting reflector panels thereon, inwardly projecting flanges on the bottom edges of the reflector panels, and louvers adapted to be supported upon said flanges transversely of the trough and comprising strips with laterally projecting arms at the ends thereof for holding said strips in edgewise position and for abutting adjacently-positioned strips to effect uniform spacing of the louvers.

30 6. The combination of a lighting trough having downwardly-depending side panels, ledge members disposed at different heights upon and extending longitudinally of the inner faces of said panels, and louvers
35 adapted to be supported upon said ledges transversely of the trough and comprising strips with laterally-projecting arms at the ends thereof for holding the strips in edge-wise positions relative to the ledges and for abutting adjacently-positioned strips to effect uniform positioning of the louvers.
40

7. The combination with a lighting trough having downwardly-depending side panels, of a continuous slotted support at the bottom edge of each panel, and louvers adapted to be supported by said means transversely of the trough and comprising strips with endwise projections thereon, said projections being adapted to be received each in a pair of slots whereby the louvers may be selectively spaced and retained in endwise positions across the opening between the panels.

55 8. In an illuminating device the combination of a lighting trough open at bottom, illuminating means in the trough, reflectors in said trough, flange members disposed adjacent the bottom of the trough, a plurality of independent individual louvers extending across the open bottom of the trough and supported by said flanges, and means for effecting uniform parallel spacing of said louvers.

9. In combination a lighting trough comprising reflector panels, means receiving and positioning a lighting element between said

panels and means comprising a series of independent louver strips and means to effect uniform spacing of the louvers and adjustment thereof longitudinally of the lighting trough.

10. In an illuminating apparatus a pair of spaced sidewalls, a receptacle supporting apertured plate vertically adjustable between said walls, receptacles adjustable longitudinally on the apertured plate, lamps in said 75 receptacles and depending below the plate, wiring disposed in the channel between the side walls and above the plate, means for closing the top of said channel and reflector panels depending from the bottom edges of 80 said sidewalls.

11. In a device for producing continuous lighting, troughs of indeterminate length comprising side wall members having vertically spaced plate supporting ledges, top cover members, an apertured plate on the ledges, lamp receptacle members supported in longitudinally adjustable relation on the apertured plate, reflector panels depending from the sidewalls and adapted for end to end mounting with similar reflector panels, end walls for the trough so developed and independent, self spacing louvers supported by and extending transversely of the open bottom of said trough. 85 90 95

In testimony whereof, I have hereunto subscribed my name this 12th day of September, 1930.
